(57) **CLAIM**

The ornamental design for a lamp post of a lamp, as shown and described.

DESCRIPTION

FIG. 1 is a top and front perspective view of a lamp having a lamp post showing my new design;

FIG. 2 is a front elevation view thereof;

FIG. 3 is a top plan view thereof;

FIG. 4 is a top and front perspective view of the lamp post in the lamp of FIG. 1, shown without the lamp shade and the lamp base for clarity of disclosure;

FIG. 5 is a bottom and front perspective view thereof;

FIG. 6 is a front elevation view thereof;

FIG. 7 is a top plan view thereof; and,

FIG. 8 is a bottom plan view thereof.

The undisclosed side views and rear view of the lamp post are identical to the front view shown in FIGS. 2 and 6. The undisclosed bottom view of the lamp does not show any feature of the claimed Design.

The broken lines in the drawings illustrate portions of the lamp post of a lamp which forms no part of the claimed design.

The shading lines shown in the views represent the approximate three-dimensional surface contour of the claimed design, and the different shading patterns in the upper and lower portions of the lamp post are intended to represent contrasting colors.

The break lines in the drawings indicate that the appearance of any portion of the lamp post of a lamp between the break lines forms no part of the claimed design.
